ELECTRICAL DISCHARGE DEVICE

Reinhold Rudenberg, Berlin-Grunewald, and Max Steenbeck, Berlin-Siemensstadt, Germany, assignors to Westinghouse Electric & Manufacturing Company, East Pittsburgh, Pa., a corporation of Pennsylvania

Application April 22, 1933, Serial No. 667,486
In Germany April 25, 1932

8 Claims. (Cl. 250—27)

Our invention relates to electrical discharge devices and especially to the combination of such devices with a control circuit therefor.

An object of our invention is to provide a control circuit utilizing large current densities in the control of an electrical discharge device.

Another object of our invention is to provide a control circuit that shall momentarily charge the control electrode of an electrical discharge device.

Another object of our invention is to provide a control circuit for an electron discharge device utilizing heavy currents in which the grid is not unduly heated.

Other objects of our invention will be apparent through reading the following specification, taken in connection with the accompanying drawing, in which:

Figure 1 is a diagrammatic view of a preferred system incorporating my invention; and

Fig. 2 is a diagrammatic view of a modification of the system disclosed in Fig. 1.

The electrical discharge device 10 in Fig. 1 may be of the usual vacuum type, including the anode 11, grid 12, and cathode 13. The cathode 13 may be an incandescent cathode, although other types of cathodes may be used, such as a mercury cathode or a glow cathode.

When a discharge has been initiated between the anode 11 and the cathode 13, it is possible to extinguish it by causing a condenser to send a current impulse momentarily in an opposite direction through the tube. This method has the drawback that it effects the main current circuit, and also that it requires relatively large extinguishing capacities.

The use of a grid to extinguish the discharge, as taught by the prior art, has the drawback that it is operable at relatively small current densities only and fails at larger current densities. The failure of the grid in the devices of the prior art with large current densities is caused by the fact that the blocking action of a negatively charged grid located in the path of the discharge is partially counteracted or neutralized by layers of positive ions which collect on or around the grid wires. The grid wires act only in a very small and definitely limiting area in a manner to block the discharge. The greater part of the meshes of the grid, however, remain penetrable. If a very high negative grid voltage is connected to the grid, the positive ion stream will cause the highly charged grid to glow, whereby it will emit electrons and lose completely its blocking action.

According to our invention, the discharge is extinguished with the help of the grid 12 lo-

cated in the path of the discharge by momentarily charging the grid to a very high negative potential, so that the thickness of the layer of the positive discharge clouds surrounding the grid will be larger than the width of the openings in the grid. The instantaneous extinguishment of the discharge is thereby effected. The length of time of the impulse serving to extinguish the discharge is less than the time in which the grid can be heated to a temperature, 10 wholly or locally, by the grid current to cause emission of the electrons mentioned above.

We prefer to have the control grid 12 made of meshes as small as possible without having the grid heated to too great a temperature by 15 the discharge. Grids having a very small mesh increase the resistance of the discharge path to a large degree, and, therefore, result in the development of a large amount of heat in the neighborhood of the grid. It will probably be 20 preferable to select a dimension of one-half to one millimeter for the meshes. The grid is so arranged that the discharge from the cathode can reach the anode only by passing through the grid. This, of course, may be accomplished by 25 extending the grid completely across the tube 10, or by substantially completely surrounding the active surface of either the anode 11 or cathode 13 with the grid.

The control circuit whereby the grid is momentarily charged may be one of several forms, but a preferred form is disclosed in Fig. 1. A supersaturated iron core 14, and its associated circuits, is utilized to obtain a very sharp voltage peak. The magnetism of the core is provided by the coils 15 supplied by the alternator 16. The magnetic flux through the core is controlled or regulated by the coil 16 around the core and connected to the resistance 17 and current supply 18. The coil 19 also around the 40 core, which is in shunt with the condenser 20, provides the means of supplying the high-voltage peak to the grid 12.

It is desired that the charging of the current be effected very rapidly, such as on the order 45 of 10^{-5} to 10^{-6} seconds. The momentary charging of the grid is accomplished by placing the spark gap apparatus 21 in series between the grid 12 and the iron core and its associated circuits.

The result of this arrangement is that the momentary charging of the grid to a high negative potential will extinguish the discharge even at high current densities without heating the grid to a temperature that will neutralize its 55

blocking action. The passage of current through the circuit 22, 23 will be interrupted, as desired, without being effected by the strength of the current therethrough. The use of the condenser 24 shunting the tube is optional.

5 After the negative impulse has been reduced to zero, a small blocking voltage might be connected to the grid 12 to prevent reignition of the discharge. It is preferable, however, that this small blocking voltage be connected to another 10 grid, such as the grid 25 in Fig. 2. This grid 25 may be charged at a low negative potential by any suitable means, as by the battery 26, illustrated. The grid 25 will prevent reignition of the discharge following the extinguishment 15 of the discharge, where the grid 12 may have a positive oscillatory charge for a time.

While we have illustrated the embodiments of our invention, it will be apparent to those skilled in the art that various changes and modifications 20 may be made therein without departing from the spirit and scope of our invention, and it is desired, therefore, that only such limitations shall be imposed thereon as are indicated in the prior art or are set forth in the appended 25 claims.

We claim as our invention:

1. In combination, an electrical discharge device having an anode, cathode and control electrode, and a control circuit for said device, said 30 control circuit having means for momentarily charging said control electrode for a period in the order of 10^{-5} seconds.
2. In combination, an electrical discharge device having an anode, cathode and two grids, and 35 a control circuit for said device, said control circuit having means for momentarily charging one of said grids to a high negative potential and means for charging the other grid at a low negative potential.
3. In combination, an electrical discharge device having an anode, cathode and control electrode, and a control circuit for said device including a source of potential and a spark gap apparatus for momentarily charging said control electrode.

4. In combination, an electrical discharge device having an anode, cathode and control electrode, and a control circuit for said device including a source of potential and a spark gap apparatus and a supersaturated iron core circuit for momentarily charging said control electrode to a high negative potential. 5

5. In combination, an electrical discharge device having an anode, cathode and two grids, and a control circuit for said device, said control circuit including a source of potential and a spark gap apparatus for momentarily charging one of said grids and means for charging the other of said grids at a low negative potential. 10

6. In combination, an electrical discharge device having an anode, cathode and two grids, and a control circuit for said device, said control circuit including a source of potential and a spark gap apparatus and a supersaturated iron core circuit for momentarily charging one of said grids to a high negative potential and means for charging the other of said grids at a low negative potential. 15

7. The method of extinguishing discharges in 20 vacuum containers by means of a grid located in the discharge path and which is wrapped up by positive space discharge clouds which comprises charging said grid with a high negative potential for only such a short period that the grid is not heated to a temperature capable of 25 causing an electron emission in the positive space discharge clouds which form around said grid. 30

8. In combination, an electrical discharge device having an anode, cathode and control electrode, and a control circuit for said device including a source of potential and a breakdown apparatus and a supersaturated iron core circuit for momentarily charging said control electrode to a high negative potential. 35 40
